ALKYLANILINEMONOSULPHONIC ACIDS
AND THEIR MANUFACTURE

Samuel Coffey and Norman Hulton Haddock,
Blackley, Manchester, England, assignors to
Imperial Chemical Industries, Limited, a cor-
poration of Great Britain

No Drawing. Application January 14, 1937, Se-
rial No. 120,632. In Great Britain January 17,
1936

10 Claims. (Cl. 260—129)

This invention relates to new alkylaniline-
monosulphonic acids and their manufacture.

In these new alkylanilinemonesulphonic acids,
the alkyl group has 6-18 carbon atoms, and is
5 directly attached to the benzene nucleus, and
there may be other substituents directly attached
to the benzene nucleus, e. g. bromo, chloro,
methyl and hydroxy substituents.

These new alkylanilinemonesulphonic acids are
10 valuable dyestuff intermediates.

According to the process of the invention we
make the new alkylanilinemonesulphonic acids
by treating alkylanilines, in which the alkyl
group has 6-18 carbon atoms, and is directly at-
15 tached to the benzene nucleus and in which there
may be other substituents directly attached to
the benzene nucleus, e. g. bromo, chloro, methyl
and hydroxy substituents, with a sulphonating
acid. Two suitable sulphonating acids are fum-
20 ing sulphuric acid and chlorosulphonic acid.

The alkylanilines which are used as starting
materials in the process of our invention may
be made from the corresponding anilines or
N-alkylanilines by heating them, in the presence
25 of a halide of zinc or cobalt, with saturated pri-
mary aliphatic alcohols having 6-18 carbon
atoms. In this process the anilines may be wholly
or partly replaced by their hydrochlorides or
hydrobromides, and the N-alkylanilines may be
30 wholly or partly replaced by their hydrochlorides
or hydrobromides, or partly replaced by the hy-
drochlorides or hydrobromides of the parent
anilines. Examples of the alcohols used in mak-
ing these alkylanilines are hexyl, octyl, decyl,
35 otherwise known as decanol, dodecyl, tetradecyl,
hexadecyl, and octadecyl alcohol. Hexadecyl al-
cohol is the main or sole component of the al-
cohols obtained by the saponification of sperm-
acet: if this is obtained by the saponification
40 of spermacet: its purity may depend upon the
purity of the spermacet: Dodecyl and tetra-
decyl, otherwise known as myristyl alcohol, are
obtained by the reduction of the mixed fatty
acids obtained from coconut oil and palm oil.
45 Other alcohols are likewise obtainable by reduc-
tion of the fatty acids of natural fats and oils.
(See, for instance, Bouveault and Blanc, Bull.
Soc. Chem. Series 3, vol. 3, pages 674 et seq. and
1210 et seq.) The alcohols include mixed alco-
50 hols, for instance technical "lorol" which con-
sists of the mixed alcohols from coconut oil fatty
acids. The alkylanilines include those specifica-
tion, although these may not always be pure
55 compounds or single chemical compounds.

One object of our invention is the provision
of new alkylanilinemonesulphonic acids, the alkyl
group of which has 6-18 carbon atoms, and is
directly attached to the benzene nucleus, and
in which there may be other substituents directly 5
attached to the benzene nucleus, e. g. bromo,
chloro, methyl and hydroxy substituents.

Another object of our invention is the provi-
sion of valuable dyestuff intermediates.

A still further object of our invention is the 10
provision of a process for the manufacture of
the said new alkylanilinemonesulphonic acids,
which comprises treating alkylanilines in which
the alkyl group has 6-18 carbon atoms and is
directly attached to the benzene nucleus and in 15
which there may be other substituents directly
attached to the benzene nucleus, e. g. bromo,
chloro, methyl and hydroxy substituents, with
a sulphonating acid. Further objects of our in-
vention will appear hereinafter. 20

The following examples, in which parts are by
weight illustrate but do not limit the invention.

Example 1.—20 parts of p-dodecylaniline are
dissolved in 150 parts of 100% sulphuric acid
at 10-15° C. 70 parts of fuming sulphuric acid 25
(20% free SO₃) are gradually added, and the
mixture is stirred for half an hour at 10-15° C.,
when it is poured into a mixture of ice and water.
The precipitate is filtered, washed with water
and dried. 30

The sulphonic acid is a white powder, slightly
soluble in water, but readily soluble in water con-
taining a little sodium hydroxide, sodium car-
bonate or ammonia. Its dilute solutions froth
on shaking, and its concentrated solutions form 35
gels on standing.

On treating with bromine (see Abderhalden,
Handbuch der Biologischen Arbeitsmethoden,
1933, vol. 2, 2517) the acid forms a dibromo-
sulphonic acid, showing that the sulphonic acid 40
group has entered in the meta position to the
amino group, i. e. that the acid is 4-dodecyl-
aniline-3-sulphonic acid.

p-Dodecyl-o-toluidine is sulphonated similarly,
the resulting sulphonic acid resembling the 45
4-dodecylaniline-3-sulphonic acid described
above.

Example 2.—52 parts of p-dodecylaniline are
dissolved in 105 parts of tetrachloroethane and
a solution of 23.3 parts of chlorosulphonic acid 50
in 25-30 parts of tetrachloroethane added in 20
minutes. The temperature rises during the ad-
dition, and at about 80° C., hydrochloric acid
is evolved. When all the chlorosulphonic acid
is in, the temperature is raised to 120° C., in one 55

hour, during which time hydrochloric acid is rapidly evolved, and then to 140° C. in 10 minutes, after which, evolution of hydrochloric acid ceases. The mixture is cooled, poured into 5 500-600 parts of water, neutralized with ammonia, the tetrachloroethane separated, and the clear alkaline aqueous solution is acidified with hydrochloric acid. The precipitate is filtered, washed with water, and dried.

10 The product is a colourless microcrystalline powder, almost insoluble in water, and only sparingly soluble as its sodium salt.

When treated with excess of bromine, the sulphonic acid forms a dibromo derivative, while the 15 sulphonic acid group is split off as sulphuric acid, showing that it occupied an ortho position to the amino group, i. e. that the sulphonic acid is 4-dodecylaniline-2-sulphonic acid.

20 p-Dodecyl-o-toluidine is sulphonated similarly and the resulting sulphonic acid has similar properties to the 4-dodecylaniline-2-sulphonic acid just described.

Example 3.—5 parts of p-decylaniline are dissolved in 30 parts of tetrachloroethane and treated 25 with 2.5 parts of chlorosulphonic acid as described in Example 2. After heating to 140° C., the mixture is cooled, poured into 100 parts of water and the solution boiled. The solution is neutralized with ammonia, evaporated to dryness, 30 and the ammonium-4-decylaniline-2-sulphonate extracted with alcohol. The ammonium salt crystallizes in shining leaflets. Both the ammonium and sodium salts are fairly readily soluble in water.

35 Example 4.—p-Tetradecylaniline is treated with chlorosulphonic acid as described in Example 2, 55 parts of p-tetradecylaniline being used instead of 52 parts of p-dodecylaniline.

40 4-tetradecylaniline-2-sulphonic acid is obtained as a colourless solid, sparingly soluble in water, and its ammonium and sodium salts are moderately and sparingly soluble respectively.

Example 5.—22 parts of p-hexadecylaniline are dissolved in 150 parts of 100% sulphuric acid at 45 15° C. 70 parts of fuming sulphuric acid (20% free SO₃) are gradually added, and the mixture stirred for an hour at 15° C., when it is poured into a mixture of ice and water. The 4-hexadecylaniline-3-sulphonic acid is filtered, washed 50 with water and dried. It is sparingly soluble in water.

Example 6.—p-Aminohexadecylbenzene is treated with chlorosulphonic acid in tetrachloroethane as described for p-dodecylaniline in Example 2.

55 4-hexadecylaniline-2-sulphonic acid is obtained.

As many apparently widely different embodiments of this invention may be made without departing from the spirit and scope thereof, it is 60 to be understood that we do not limit ourselves to the specific embodiments thereof except as defined in the appended claims.

We claim:

1. Alkyylaniline-sulphonic acid in which the alkyl group is a saturated aliphatic radical having 6 to 18 carbon atoms and is directly attached to the benzene ring, in which the benzene ring is substituted by sulphonic acid in one of the positions meta and ortho to the amino group, and a free position of the benzene ring is substituted by one of the group consisting of hydrogen, 10 methyl, chloro, bromo and hydroxy.

15 2. Dodecylaniline-sulphonic acid in which the benzene ring is substituted by sulphonic acid in one of the positions meta and ortho to the amino group, and a free position of the benzene ring is substituted by one of the group consisting of 15 hydrogen, methyl, chloro, bromo and hydroxy.

3. 4-dodecylaniline-3-sulphonic acid.

4. 4-dodecylaniline-2-sulphonic acid.

5. The mono-sulphonic acid of p-dodecyl-o-toluidine in which the benzene ring is substituted 20 by the sulphonic acid group in one of the positions ortho and meta to the amino group.

6. The process which comprises interacting an alkylaniline compound in which the alkyl group is a saturated aliphatic radical having 6 to 18 25 carbon atoms directly attached to the benzene nucleus, in a non-aqueous reaction medium with a sulphonating acid until an alkylaniline-mono-sulphonic acid is formed.

7. The process which comprises dissolving an 30 alkylaniline compound in which the alkyl group is a saturated aliphatic radical having 6 to 18 carbon atoms directly attached to the benzene nucleus in 100% sulphonic acid, adding fuming sulphuric acid and interacting therewith at about 35 10° to about 15° C. until an alkylaniline-mono-sulphonic acid is formed.

8. The process which comprises dissolving an 40 alkylaniline compound in which the alkyl group is a saturated aliphatic radical having 6 to 18 carbon atoms directly attached to the benzene nucleus in tetrachlorethane, adding chlorosulphonic acid and interacting therewith at about 45 80° to about 140° C. until an alkylaniline-mono-sulphonic acid is formed.

9. The process which comprises adding about 70 parts of fuming sulphuric acid to a sulphuric acid solution containing about 20 parts of dodecylaniline, and interacting at temperatures of about 10° to about 15° C. until dodecylaniline-50 mono-sulphonic acid is formed.

10. The process which comprises adding about 2 parts of dodecylaniline dissolved in tetrachloroethane to a tetrachlorethane solution containing 55 about 1 part of chlorosulphonic acid, raising the temperature of the mixture to about 140° C. and heating at said temperature until a dodecylaniline-mono-sulphonic acid is formed.

SAMUEL COFFEY.
